UNITED STATES PATENT OFFICE.

LOUIS JENSEN, OF CHICAGO, ILLINOIS, ASSIGNEE TO UNITED AUTOGRAPHIC REGISTER COMPANY, OF CHICAGO, ILLINOIS, A CORPORATION OF ILLINOIS.

FILING MECHANISM FOR AUTOGRAPHIC REGISTERS.

Application filed November 1, 1926. Serial No. 145,526.

My present invention relates to autographic registers and it has more particular reference to registers in which one of the strips has its tickets detached and deposited in a filing space or compartment in the register casing. Specifically stated the present structure relates to means that are adapted to automatically engage the ticket after it has been impaled upon the filing pins and immediately upon the completion of the severing operation said means will oscillate sufficiently to sweep the severed ticket from the delivery mechanism into the filing space. In this connection it will be noted from the following description and the accompanying drawings that the tickets are each turned over by the oscillating structure or "kicker" arms so that said tickets are deposited each face downward in a pile with the first ticket at the bottom, so that when the stored tickets are removed and the pile turned over the tickets will be in their proper order.

The elements of the present invention are actuated by the feed and delivery mechanism of the register in co-action with the filing-pin mechanism so that the cycle of operation is wholly automatic from the commencement of the feed or delivery of the ticket to its deposit in the storage chamber or filing space. This comprises one of the objects of my invention, other objects being to provide a mechanism that is simple in construction, dependable in operation, and which is novel and sturdy in the arrangement and design of its parts. A further object resides in providing a structure of this character that is economical to produce so that it will not increase the cost of manufacture of the register.

I prefer to accomplish the several objects and to carry out my invention in substantially the manner hereinafter described and as more particularly pointed out in the claims, reference being herein made to the accompanying drawings that form a part of this specification.

In the drawings:

Figure 1 is a fragmentary elevation of the operating portion of an autographic register to which my invention is applied.

Figure 2 is a vertical transverse section taken beyond the delivery and filing mechanism and showing my improvements or "kicker" device in elevation.

Figure 3 is a vertical longitudinal section

of the operating portion of the register with the parts in their positions just before the filing pins engage or impale the paper.

Figures 4 and 5 are schematic views or portions of the structure disclosed in Fig. 3 and showing the parts in two subsequent positions. Fig. 4 shows the paper strip as impaled upon the pins and delivered to the end of the ticket and the cutter in the act of severing the delivered ticket from the strip, 65 while Fig. 5 shows the positions assumed by the parts during the action of the "kicker" device.

Figure 6 is a schematic view of a portion of a paper strip such as employed in autographic registers of the type disclosed herein.

The drawings are in a sense merely schematic for the purpose of illustrating a preferred or typical embodiment of my invention, and in said drawings I have employed similar reference characters to designate like parts wherever they appear throughout the several views.

The casing of the register comprises longitudinal side-walls 10, a bottom wall or base 11, and a platen 12 the edges of which are connected with the upper edges of the side walls 10. While the register is adapted for the use of several strips of paper 13 only one strip is illustrated for convenience and this strip is shown as being cut into tickets that are deposited into the filing space in the delivery end of the register. The strip of paper 13 is provided with spaced longitudinal rows of apertures 14 that are arranged in pairs at the end of each ticket which apertures are utilized for filing the tickets as well as in connection with the feed and registration of the tickets of a set when a plurality of strips are employed. The feed mechanism, the restarter, and the registering devices are of the type illustrated in the application of Allen B. Cooke, which was filed September 14th, 1926, Serial No. 135,452, 100 and consists of devices that co-act with the strips and the perforations thereon for advancing, arresting, registering, and restarting the strips. Briefly this structure consists of upper and lower feed-shafts 15 and 16 that are rotated in opposite directions by small and large gears 17 and 18 upon the ends of the respective shafts, and intermediate the ends of the shafts are provided with opposing feed disks 19 and 20 respectively 110

that are of the same diameters as the respective gears, and are of less thickness than the diameter of the strip apertures 14. The disks normally feed or advance the paper until a set or pair of apertures 14 register with the contacting or opposed portion of the disks when the latter become ineffective to further advance the paper, and as the apertures determine the ends of the tickets the arresting of the advance thereof occurs whenever the end of a ticket is reached. After the succeeding ticket has been made out it of course is necessary to again advance the paper which is done through the medium of the re-starter in the form of lateral lugs or blocks 21 and 22 projecting from the respective shafts 15 and 16, which re-starter blocks have convex peripheries of the same curvature as the disks 19 and 20 and are of the same radii as the disks. The re-starter mechanism is positioned intermediate the disks and is therefore intermediate the apertures in the paper so that the re-starter is effective on the paper when the disks are ineffective, but the surfaces of the blocks do not oppose each other each time they rotate because of the fact that the ratio of the gears 19 and 20 is seven to five and brings the feed surfaces of the blocks into opposition with each other only at the end of the tickets. The feed and re-starter mechanism are actuated by a drive shaft 23 journaled in the side-walls of the casing and one end thereof is provided with an operating crank 35 or handle 24 while the opposite end is provided with a gear 25 that meshes with an idle gear 26 mounted on a stud 27 projecting from the adjacent wall of the casing. The idle gear 25 meshes with gear 28 on the end of the lower feed shaft 16 opposite gear 18 and shaft 23 is adapted to be given two revolutions and then arrested by a stop 29 upon the oscillating member 30 of any suitable stop-mechanism (not shown).

Mounted in the side-wall 10 so as to project therethrough is an intermediate spindle 31 having upon its outside end a gear 32 and upon its inside end a pinion 33, the former being in mesh with the idle gear 25. A bearing bracket 34 is secured to and arises from the bottom or base 11 of the casing and in its upper end there is journaled a cam-shaft 35 that also has a bearing in the casing wall below the spindle 31, while intermediately of its end the cam-shaft is provided with a gear 36 that meshes with the aforesaid pinion 33. Next to the gear 36 the shaft 35 is provided with an edge cam 37 that is adapted to operate, by suitable mechanism (not shown), the cutter blade 38 and the clamping bars 39 that extend transversely across the register in front of the platen and above a longitudinal slotted co-acting bar 40. The clamping and cutting mechanism is timed so as to move downwardly to the bar 40

over which the paper is disposed subsequent to the arrest of the paper advance. As will be seen the bar 40 is provided with a downward curved surface 41 and adjacent thereto is a similarly curved shield 42 affording a 70 guide passageway through which the paper advances to the filing space.

A pair of automatically returnable rock shafts 43 and 44 are journaled in the side-walls of the casing close to the base 11 and are each held in their normal positions by coiled springs 45 and 46 respectively. Upon the shaft 43 there is mounted one or more filing-pins 47 the upper portions 48 of which are preferably curved as shown and are tapered towards their upper ends. There is a partition 49 below the bar 40, which extends transversely across the casing from side wall to side wall and in normal position, that is, when the paper begins 85 to advance, the pins are in the position shown in Fig. 3. The ends of the pins are spaced apart a distance corresponding to the transverse spacing of the paper apertures 14, so that when the paper has moved down into the filing space a slight distance the pins are automatically oscillated towards the partition 49 and against the adjacent surface of the paper and, as the latter advances, the ends of the pins will enter the apertures 14, so that the advanced portion of the strip is caught upon the pins and the strip will move down to the lower end of the pins as shown in Fig. 4. This movement of the pins is controlled by a cam arm 50 secured to the cam shaft 35 that engages a short lever 51 projecting radially from the filing-pin rock-shaft 43. When the cam arm engages the lever 51, which is after the paper has been severed and filed it will rock 105 shaft 43 backward against the urge of the spring 45 to the position shown in Figs. 3 and 5.

In order to prevent the paper strips remaining in the position shown in Fig. 4, 110 after the clamps and severing blades are withdrawn, there is provided a suitable "kicker" mechanism. This consists of a pair of arms 52 projecting from the rock-shaft 44 upwardly to a normal position against the partition 49 and terminate just below the bar 40. The upper ends 53 of the arms 52 are bent laterally as shown in Fig. 2, and may, if desired, be covered with a suitable rubber sleeve 54 to protect the same and deaden the noise incident to their striking against the partition. A lever 55 projects radially from rock-shaft 44 alongside one of the "kicker" arms for the purpose of actuating the latter. A cam element 56 is mounted on cam-shaft 35 and in its path of travel engages the lateral end 57 of a slide bar 58 mounted upon the adjacent side wall of the casing, which at its opposite end provided with a lug 59 that engages the lever 120 125 130

55. The slide bar is provided with a longitudinal slot 60 through which headed screws 61 pass for mounting and permitting the sliding movement of the bar. In their 5 normal positions the "kicker" arms, as shown in Figs. 3 and 4, are between the paper strip 13 and the partition 49, and the cam 56 and slide bar 58 are so timed in operation that when the clamps and cutter are withdrawn 10 the rock-shaft 44 will be oscillated so that the upper ends of the arms 52 will move quickly away from the partition to the position shown in Fig. 5 thus withdrawing the cut edge of the paper from the bar 40 and 15 delivering the ticket into the filing space with its face side down. Just prior to the arresting of the operating handle 24 the cam arm 56 moves away from the slide bar and the "kicker" arms return to normal 20 position (Fig. 3) against the partition so that the next ticket that is advanced will clear the "kicker" arms.

Back of the bar 40, and forming a continuation of the platen 12, there is a transverse guide plate 62, the edge of which nearest the bar is spaced therefrom and is bent or deflected in an oblique direction downwardly. The space between the plate and the bar provides a guide slot through which 25 30 the paper strips which are not to be filed in the forward compartment will be advanced downward on the opposite side of the partition from the strip being filed and are readily accessible through an opening 35 40 63 in the casing wall. The outer edge of plate 62 is beveled to provide a severing or knife edge against which the thus advanced strip or strips are pulled and detached from the remainder, and the bar 40 performs the function of a separator when a plurality of strips are used to direct the advanced portions of the strips into their respective paths.

What I claim is:—

- 45 1. In an autographic register in which a paper strip is intermittently advanced, impaled upon a filing-pin and severed into tickets, an arm pivotally mounted in the register having a lateral portion adapted to engage the impaled ticket, and cam means actuated by the advancing mechanism for moving said arm whereby the lateral portion thereof inverts the impaled ticket and deposits the latter in a filing space.
- 50 55 2. In an autographic register, a platen,

means for intermittently advancing an apertured strip across said platen including means for separating the strip into tickets, a pivoted impaling pin, means for actuating said pin to cause it to enter an aperture in 60 the strip to file a ticket, a pivoted arm that engages the impaled ticket and moves the same away from the separating means, a reciprocating slide for actuating said arm, and a cam for moving said slide in the working stroke thereof.

3. In combination with an autographic register in which a paper strip is intermittently advanced, impaled on a filing-pin, and separated into tickets, a pivoted arm that engages the impaled ticket and inverts the same, a reciprocating slide for actuating said arm, and a cam for moving said slide in the working stroke thereof.

4. In combination with an autographic 75 register in which a paper strip is intermittently advanced, impaled on a filing-pin, and separated into tickets, a rock-shaft, an arm thereon that engages the impaled ticket and moves the same away from the separating 80 means, a reciprocating slide, a fixed lever projecting from said shaft into the path of said slide, and means for moving said slide.

5. In combination with an autographic register in which a paper strip is intermittently advanced, impaled on a filing-pin, and separated into tickets, a rock-shaft, an arm thereon that engages the impaled ticket and moves the same away from the separating 85 means, a reciprocating slide, movable towards and away from said shaft, a lever projecting from said shaft and engaged by said slide, and a cam for moving said slide.

6. In an autographic register, a platen, means for intermittently advancing an apertured strip across said platen including devices for separating the strip into tickets, an impaling pin upon which the tickets are separately filed, a rock-shaft, an arm thereon that engages an impaled ticket and moves 100 the same away from the separating devices, a lever fixed on and projecting from said shaft, a slide, and a cam actuated by the advancing means for moving the slide and causing the same to engage the lever and 105 rock said shaft.

Signed at Chicago, in the county of Cook, and State of Illinois, this 25th day of October, 1926.

LOUIS JENSEN.
